CHAIR IRON

David R. Collier and Henry W. Sheldrick, Gardner, Mass., assignors to Collier-Keyworth Company, Gardner, Mass., a corporation of Massachusetts

Application November 27, 1935, Serial No. 51,849

11 Claims. (Cl. 155—77)

This invention relates to chair irons for tilting chairs and has for an object to provide an iron which will be noiseless, free in action, have long life, and provide for easy replacement of springs.

- 5 In order to provide noiselessness and freedom in action, the spring elements are made of deformable material such as rubber, the rubber being so compounded as to resist the effects of air and climatic changes so as to have long life.
- 10 The spring elements are so housed and the tilting forces are so impressed thereon as to relieve the fulcrum pin from forces other than those due to the weight of the chair and its occupant, and the spring element mountings are such that
- 15 proper replacements are rendered easy.

For a more complete understanding of this invention, together with further objects and advantageous constructions, reference may be had to the accompanying drawing, in which

- 20 Figure 1 is a side elevation of a chair iron embodying this invention and showing adjacent portions of the chair.

Figures 2 and 3 are detail sections on lines 2—2 and 3—3, respectively, of Figure 1 and to a larger scale.

Figure 4 is a central longitudinal section through the iron with the related parts being arranged in horizontal chair seat position.

- 25 Figure 5 is a view similar to Figure 4, but showing parts in chair-tilted position.

Figure 6 is a perspective view of a rocking spring seat lever.

Figure 7 is an exploded perspective of a spring element and its seat plates.

- 30 Referring to the drawing, the iron comprises a supporting member 1 box-shaped in cross section secured to the upper end of a chair spindle 2, which is shown as formed with screw threads to facilitate raising and lowering the chair. This

35 spindle is threaded into the chair base 3 (see Figure 1) in any suitable or usual manner. The box-shaped member 1 is shown as formed of two channel-shaped portions 5 and 6, the flanges 7 of the portion 5 being down-turned and positioned between the up-turned flanges 8 of the member 6, the two parts being secured together as by rivets 9. The upper end of the spindle 2 passes through both upper and lower web portions 10 and 11 of the parts 5 and 6 and is

40 shown as riveted over as at 12 against the top of the web member 10.

45 The seat-carrying member comprises a channel-shaped element 15 having a central web 16 and downwardly projecting flanges 17, and overlapping the web and each flange is shown an

angle spider member 20 to the upper flange 21 of which may be secured the chair seat 22 (see Figure 1) in any suitable manner. The angle members 20 are shown as secured to the element 15, as by the rivets at 24. The member 15 is pivoted to the spindle-carried member 1 as on the transverse pin 25. As shown in Figure 3, this pin 25 may have a squared portion 26 adjacent to one or both ends which fits in a mating opening in the flange 17 so as to prevent the turning of the pin 25 with respect to the seat-carried member. The overlapping portions of the flanges 7 and 8 may have extended therethrough a bushing 27 of a suitable bearing metal, this bushing being rockable on the pin 25.

Extending longitudinally within the box-shaped spindle-carried member 1 is a lever 30 shown detached in Figure 6. This lever has opposite side walls 31, a base 32, which extends for a portion of its length and a top member 33. The base 32 and the side members 30 are shown as integral, being formed as parts of a channel member and the top member 33 is shown as formed of a second channel member having its side flanges 34 fitted between the sides or flanges 31 and secured in position therein as by the rivets 36. This lever 30 is provided with opposed journal openings 35 in its side walls 31 and through these openings 35 the pivot pin 25 also passes. Thus the lever 30 is pivoted for rocking motion 30 coaxially with the pivotal connection between the spindle-carried member 1 and the seat-carrying member 15.

The base 32 of the lever 30 is shown as provided with an offset portion 40 forming a rounded projection on its upper face, while the part 33 has a similar offset portion 41 forming a downward projection on its lower face. These projections 40 and 41 serve as centering means for one end of each of deformable spring blocks 45 of rubber or the like. The web 5 and the web 11 of the spindle-carried member are formed with corresponding offset portions 47 to form block centering means oppositely disposed to the elements 40 and 41.

Each of the blocks 45 is shown as provided with a central perforation 50 with which these projecting portions 40, 41 and 47 cooperate, but in order to facilitate the placing and removal of these spring blocks, there is interposed between 50 each end of each block and the lever and the spindle-carried portion, a metal plate or disk such as 51, each having a central offset portion 52 forming a hollow on one side to receive the mating projection from the lever or spindle-

carried member and a projection on the other face for engagement in the adjacent end of the perforation 50 of the respective block 45.

The spindle-carried member may have an upwardly projecting abutment portion 55 at the forward end of each flange 7 for engagement with the lower face of the top flange 21 of the spider angle thereabove, thus to determine the limit of forward motion of the chair seat and determining its normal horizontal position and similar stops 56 limit the backward tilting.

Initial compression or loading of the blocks 45 independent of the angular position of the seat-carrying member in order to determine the resistance produced thereby to backward tilting of the chair is determined by an adjustable abutment shown as a screw 60 provided with a hand wheel 61. This screw is threaded through a portion 63 at the rear end of the lever 30 and shown as formed of a part of the member 33, this screw bearing at its upper end against an upwardly bent portion 62 at the rear end of the seat member 15 and rearwardly of the ends of the flanges 17. It will be noted that the spring blocks are arranged on opposite sides of the pivot axis on the pin 25 and on opposite sides of the lever so that both are compressed together or released together.

It will also be noted that in the normal position of the parts when the seat is horizontal and the tension is removed by adjustment of the screw 60, the confronting faces of the lever and the parts of the spindle-carried member between which the spring blocks are positioned are non-parallel, the narrower portions of the space for the springs being positioned toward the pivot pin 25. This permits easy placing of the spring elements, since they can be freely inserted between their mating seat portions endwise and then pressed to a sufficient extent to snap the projections 40, 41 and 47 into position. Preferably the disks or plates 51 are initially lightly secured as by rubber cement to the ends of the spring blocks, so as to present surfaces for engagement with the mating portions of the chair iron which can be easily slid thereover. It will also be noted that when the springs are in their final positions they are substantially entirely housed between the lever and the spindle-carried member, so that the iron presents a trim and pleasing appearance.

As the chair is tilted, as shown in Figure 5, the portion 62 depresses the screw 60, which, in turn, rocks the lever 30 and applies the deforming pressure to the spring blocks. Since the lever 30 rocks with the chair seat-carrying member and is adjustably related thereto through the screw 60, this lever acts as an operative connection between the spring seats carried thereby and the chair seat-carrying member, this connection being adjustable by rotation of the screw 60. The weight of the chair seat and its occupant is transmitted from the seat-supporting member 15 through the pin 25 to the spindle-supporting member, the pin 25 inwardly of the bushings 27 and the lever 30 being entirely free from this service.

The pin 25, also is entirely free from any forces due to compression of the spring blocks, the two blocks so balancing each other in action that the pin is located in the natural rocking axis of the lever 30.

It will also be noted that in such compressed condition the relative angularity between the faces of the lever and the faces of the spindle-carried member between which the blocks are

compressed are reversed to that shown in Figure 4, thus tending to increase the holding power of the cooperating parts against the escape of the blocks from their proper positions.

From the foregoing description of an embodiment of this invention, it will be evident to those skilled in the art that various modifications and changes may be made without departing from the spirit or scope of this invention as defined by the appended claims.

We claim:

1. A chair iron having a supporting member, a chair seat-carrying member, a pivotal connection between said members, a lever fulcrumed on said supporting member, a pair of compression spring elements having opposite ends bearing on said lever and said supporting member, said springs bearing on said lever at opposite sides of its fulcrum and means for adjusting the angular relation between said lever and seat-carrying member to cause tilting of said seat-carrying member to rock said lever.

2. A chair iron having a supporting member, a chair seat-carrying member, a pivotal connection between said members, a lever fulcrumed on said supporting member, a pair of spring elements positioned between and acting on said lever and supporting member, one on each side of said lever fulcrum, said spring elements being positioned on opposite sides of said lever, and means operatively connecting said seat carrying-member and said lever.

3. A chair iron having a supporting member, a chair seat-carrying member, a pivotal connection between said members, a lever fulcrumed on said pivotal connection, a pair of spring elements positioned between and acting on said lever and supporting member, one on each side of said lever fulcrum, said spring elements being positioned one on one side and the other on the opposite side of said lever, and means operatively connecting said seat carrying-member and said lever.

4. A chair iron having a supporting member of box cross section, a chair seat carrying member pivoted to said supporting member, a lever pivoted transversely of and within said supporting member, a pair of spring blocks one positioned on each side of said lever pivot between said lever and a wall of said supporting member and on opposite sides of said lever to cause pressure to be applied to both blocks on swinging of said lever in one direction and released on swinging of said lever in the opposite direction, and an adjustable abutment between said lever and seat carrying member determining the initial pressure exerted on said blocks when said chair seat-carrying member is in non-tilted position.

5. A chair iron having a supporting member of box cross section, a chair seat carrying member pivoted to said supporting member, a lever having side walls and a pair of walls in different planes connecting said side walls, said lever being pivoted transversely of and within said supporting member, a pair of spring blocks one positioned on each side of said lever pivot between said lever side walls and reacting between said connecting walls and walls of said supporting member on opposite sides of said lever to cause pressure to be applied to both blocks on swinging of said lever in one direction and released on swinging of said lever in the opposite direction, an adjustable abutment between said lever and seat carrying member determining the initial pressure exerted on said blocks when said chair seat-

carrying member is in non-tilted position, and means determining said non-tilted position.

6. A chair iron having a supporting member of box cross section, a chair seat carrying member pivoted to said supporting member, a lever pivoted transversely of and within said supporting member, a pair of spring blocks one positioned on each side of said lever pivot between said lever and a wall of said supporting member and on opposite sides of said lever to cause pressure to be applied to both blocks on swinging of said lever in one direction and released on swinging of said lever in the opposite direction, and a screw threaded through said lever and bearing on said seat-carrying member determining the initial pressure exerted on said blocks when said chair seat-carrying member is in non-tilted position.

7. A chair iron having a supporting member having side and upper and lower walls, a chair seat-member pivoted to said supporting member, a lever having side walls pivoted transversely of and within said supporting member and having upper and lower walls on opposite sides of said lever pivot, a compression spring positioned between the lower wall of said lever and the upper wall of said supporting member at one side of said pivot, a compression spring positioned between the upper wall of said lever and the lower wall of said supporting member on the opposite side of said pivot, and operative connections from said lever to said chair-seat member.

8. A chair iron having a supporting member of box cross section, a chair seat carrying member pivoted to said supporting member, a lever pivoted transversely of and within said supporting member, a pair of spring blocks one positioned on each side of said lever pivot between said lever and a wall of said supporting member and on opposite sides of said lever to cause pressure to be applied to both blocks on swinging of said lever in one direction and released on swinging of said lever in the opposite direction, and an adjustable abutment between said lever and seat carrying member determining the initial pressure exerted on said blocks when said chair seat-

carrying member is in non-tilted position, said lever and supporting member having opposed spring seat portions non-parallel when said members are in non-tilted position, and said spring blocks having non-parallel end faces to thereby facilitate placing and removing said spring blocks between said seat portions.

9. A chair iron having a supporting member, a chair seat-carrying member, a pivotal connection between said members, a pair of spring seats carried by one of said members on opposite sides of the pivot of said connection, a pair of spring seats operatively connected to the other of said members opposite to said first mentioned spring seats and disposed on opposite faces of said other member, a pair of spring elements, each spring element being disposed between oppositely positioned spring seats, and means for adjusting said operative connection.

10. A chair iron having a supporting member, a chair seat-carrying member, a pivotal connection between said members, a pair of spring seat members on opposite sides of the fulcrum of said connection and movable with said chair seat-carrying member, upper and lower spring seats on said supporting member disposed opposite to opposite faces of said spring seat members, spring elements between said oppositely disposed spring seats and spring seat members and means for loading said spring elements independently of the angle of said seat-carrying member.

11. A chair iron having a supporting member, a chair seat-carrying member, a pivotal connection between said members, a pair of spring seat members on opposite sides of the fulcrum of said connection, and movable with said chair seat-carrying member, upper and lower spring seats on said supporting member disposed opposite to opposite faces of said spring seat members, spring elements between said oppositely disposed spring seats and spring seat members, and means for adjusting said spring seat members relative to said chair seat-carrying member.
